UNITED STATES PATENT OFFICE

EDWARD C. CORDES, OF CINCINNATI, OHIO, ASSIGNOR TO THE HYDE PARK LUMBER COMPANY, OF CINCINNATI, OHIO, A CORPORATION OF OHIO

KNOCKDOWN SHELVING

Application filed January 29, 1931. Serial No. 512,022.

This invention relates to knockdown or portable shelving and has for an object the provision of such shelving which may be set up and taken apart in a minimum of time and without requiring skilled labor for the purpose.

Another object is to provide such shelving having parts of convenient size for handling and transportation.

10 Another object is to provide a shelving, the composite units of which are easily and quickly added or removed whereby the shelving is readily adaptable to various locations and conditions.

15 Another object is to provide shelving of this kind in which attention has been given to the appearance as well as to the utility thereof.

Another object is to construct such installation having means for variable arrangement of the shelves thereof.

Another object is to provide new and efficient forms of mounting means for shelving of the class described.

20 These and other objects are attained by the means described herein and illustrated in the accompanying drawings, in which:

Fig. 1 is a front elevational view with parts broken away, of erected shelving units of the present invention.

Fig. 2 is a view taken on line 2—2 of Fig. 1, with part broken away.

Fig. 3 is a view similar to Fig. 2 but showing a modified form of structure.

Fig. 4 is a view taken on line 4—4 of Fig. 1, with parts broken away.

Fig. 5 is an enlarged cross-sectional view taken on line 5—5 of Fig. 4.

Fig. 6 is a fragmentary, cross-sectional view showing shelf-mounting means of this invention.

Fig. 7 is a cross-sectional view taken on line 7—7 of Fig. 6.

Fig. 8 is a fragmentary elevational view of upper portions of the shelving units of the invention.

Fig. 9 is a fragmentary elevational view of bottom portions of the shelving units, parts being shown in cross section.

Fig. 10 is a cross-sectional view taken on line 10—10 of Fig. 9.

Fig. 11 is a fragmentary cross-sectional view of shelving-unit connecting means and associated structure.

Fig. 12 is an end elevational view, with parts broken away, of a modified form of shelving structure of this invention.

Fig. 13 is an enlarged cross-sectional view taken on line 13—13 of Fig. 12.

Fig. 14 is an enlarged fragmentary elevational view of modified shelf-supporting means shown in the two preceding figures, a shelf being shown in cross section.

Fig. 15 is a cross-sectional view, taken on line 15—15 of Fig. 14, this view showing mounting means for continuous shelving provided by this invention.

Fig. 16 is an enlarged cross-sectional view taken on line 16—16 of Fig. 12.

Fig. 17 is a fragmentary elevational view, partly in section of shelf-mounting means illustrated in Fig. 15.

Fig. 18 is a fragmentary end view, with part broken away, of shelving structure shown on the right hand side of Fig. 1.

Fig. 19 is a cross-sectional view taken on line 19—19 of Fig. 4.

The shelving of the present invention is designed to meet the need, especially urgent under modern quick-changing business conditions, for mobility and adaptability in installations of this kind. It replaces the old style of built-in shelving which ordinarily was left behind upon movement of a business to a new location, since the shelving provided for herein does not require to be fixed to the adjacent floor and wall but is self-supporting.

At the same time, the shelving is so constructed that when set up it is firm and rigid, despite the fact that its ease of erection is a notable feature thereof. Moreover, means have been provided for making the shelving as pleasing in appearance as it is efficient in use.

The shelving of this invention is provided in units the number of which may be increased or decreased as occasion requires, one unit being readily attachable to and detachable from an adjacent unit.

Each unit comprises separate longitudinally-extending floor members or sills provided with means for receiving the vertical members, that is, the partitions and end walls. 5 The partitions are shown herein in two forms, the solid panel type and the open frame type, the latter being utilized for continuous shelving, through a series of shelving units. Special means, peculiar to this invention, are 10 provided for supporting the shelving on the vertical members, the shelves being adapted for angular positioning when such is found necessary. The top portions of the units are receivable upon the tops of the vertical members and are adapted for quick positioning by simplified means of this invention. The tops, as well as all outer surfaces and edges, are constructed with ornamental cooperating finishing members giving a unified and attractive appearance to the erected shelving.

With reference first to Figs. 1, 2, 9 and 10: each shelving unit of this invention comprises a pair of parallel floor members or sills 25, rectangular in cross section and extending longitudinally of a unit. Sills 25 are of standard uniform construction. Intermediate the ends of each sill is formed a cross gain 37 (Figs. 1, 10) extending across the edges and top face of the sill. On the upper face of each sill, at one end thereof, is fixed a bracket 26, having an arm 27 attached to the sill and a tongue 28, projecting downwardly of the end of the sill in spaced relationship therewith. The face of the sill to which arm 27 is fixed, is cross gained as at 29 (Fig. 9) to a depth equal to the thickness of arm 27. The opposite end of each sill is similarly cross gained, as at 30, upon the bottom face thereof, and in addition, said end is 40 provided with a tenon 31. To the cross gained bottom face of this end is fixed the flange 32 of an attachment member 33 (Fig. 9). Member 33 is of the same width as tenon 31 and provides the portion 34 projecting upwardly of the end of the tenon to the same plane as the upper face of the sill. Portion 34 is formed with a central receiving pocket 35 the upper edge 36 of which is slightly lower than the top edges of portion 34 adjacent thereto. Pocket 35 is adapted to receive a tongue 28 in snug relationship. The solid panel type of partition 38 is seen in Figs. 1 and 18. Each partition 38 (Fig. 1) is mortised upon its lower edge to cooperate with the cross gains 37 of a pair of positioned sills 25. The partition extends transversely beyond the front and rear sills. Adjacent its longitudinal edges, the partition is provided with rows of aligned perforations 39. The front edge of the partition has a molding strip 40 affixed thereto.

End walls 41 (Figs. 1, 2, 3, 4, 5) are now placed in position if a single unit only is to be erected. Walls 41 are similar to partitions 38 and are provided with mortises and with

similar rows of perforations aligned with those of the partition. The outer face of each wall is grooved longitudinally along the lines of perforations 39 for receiving veneer strips 42, preferably of a color contrasted with that of the walls, said strips lying flush with the outer faces of the walls. Similar cross veneer strips may be provided adjacent the top and bottom of the walls. Molding strips 43 are attached along the front edges of the walls. At one end of the unit, the mortised portions of the end wall are inserted over the tenons 31 of the sills and between the bodies of the sills and the portions 34 of the attachment members 33 (Figs. 2, 9). The wall at 50 the opposite end of a first-erected unit is positioned by the use of a special engagement member or starting shoe. This device is illustrated clearly in Fig. 11. Its purpose is to obviate the need of manufacturing a special pair of sills with tenons and members 33 at both ends rather than at one end only. The starting shoe 44 is a rigid metal member substantially U-shaped in cross section and provided on each side with pockets 45 similar to 55 pockets 35 of members 33 and similarly designed to receive the tongues 28 of brackets 26. The sides 46 of the shoe are so spaced as to receive snugly an end wall or a partition. The width of the shoe is the same as that of tenons 31 and to compensate for the latter, a block 47 is fixed upon the base 48 of the shoe.

In positioning the wall, therefore, at this end of the unit, a starting shoe is associated with each mortise on the bottom edge of the wall, the block 47 being of such thickness that the base 48 of the positioned shoe is flush with the bottom edge of the wall. The pockets 45 adjacent the inner face of the wall are now in position to receive the tongues 28 of the sill brackets 26, while the similar pockets 45 on the outer face of the wall, as well as the pockets 35 at the opposite end of the unit, are in readiness to be associated with other sills should other units of shelving be subsequently added.

The top and associated structure of the unit are likewise of standardized manufacture. Elongated brackets 49 (Figs. 4, 8) are permanently secured, one each, upon both faces of a partition 38 and upon the inner face of the end walls. Brackets 49 are placed centrally of the top edges of said members and provide an inwardly-projecting ledge 50 flush with said top edges. Ledge 50 is provided with aligned elongated perforations 51 and with strengthening bosses 52. Two top members are provided for each shelving unit. Each comprises a panel 53 of the same width as the partition and end walls and adapted to extend between the top edges of a partition and an end wall, its ends reaching half way across said edges. Adjacent the ends and extending downwardly through each panel 53, the bolts 54 are threadedly inserted,

these being receivable in perforations 51 of brackets 49 and being adapted to receive the nuts 55 for removably securing the top panels in place. The front edge of the panel 53 has a 5 downwardly-extending ribbon strip 56 (Fig. 8) attached thereto by means of an angle bracket 57 (Fig. 4) adjacent each end of the panel. A molding strip 58 is secured along the upper edge of ribbon strip 56. After the 10 two top panels of a unit have been positioned, the line of abutment of the strips 56 and 58 is covered by an ornamental block 59 (Figs. 1, 4, 8), conforming on its rear to the outline of the covered members. Block 59 is preferably formed of an inner piece 60, an outer piece 61 and a diagonally-extending central veneer piece 62, whereby said member is strengthened against repeated usage. It should be noted that the molding strips 40 15 of the partition and end walls terminate at the lower edges of ribbon strips 56. At the bottom of the unit, said strips terminate short of the floor line to accommodate a bottom molding 68 (Fig. 1) which may be attached 20 to the adjacent edges of the erected partition and end walls. Cover block 59 may be fixed to the inner end of the edge structure of one of the top panels before positioning thereof but is preferably positioned by means 25 of glue, brads or the like, after the positioning of the top panels.

At the ends of panels 53, edge structure, similar in appearance to that along the front of the panels, is provided. This structure is shown in Fig. 19, in which the molding strip 63 is formed with a rear ledge 64, of the same thickness as top panel 53 and adapted to fit snugly along the unoccupied outer half of the top edge of wall 41. This molding strip may be attached to the wall in any suitable way and extends forwardly to the same extent as front molding strip 58, the front end of strip 63 being formed in a shape complementary to the outer face of strip 58. 40 Along the lower edge of the strip a flange 65, spaced from wall 41, is provided. The ribbon strip 66 is secured between this flange and the wall 41. A block 59 (Fig. 4) is attached to molding strip 63 and ribbon strip 66 adjacent the front end thereof, and another of said blocks is attached over the abutment line of the front and end molding strips. The unit is thus provided with an attractive 45 cornice structure.

The bottom shelf 67 (Fig. 2) extends between partition 38 and an end wall 41 and is of the same width as said members. Upon its under face are attached transverse support strips 69 adapted to rest upon sills 25 and having downward extensions 70 adapted to embrace the front of the sill for precluding forward and backward movement of the shelf. The front edge of the shelf may be 50 provided along its length with a price tag or

title strip 71 extending downwardly to contact the upper edge of molding 68.

In the event that no strip 71 is needed upon the bottom shelf, said shelf may be of the plain board type 670, indicated in dotted 76 lines, Fig. 2. Shelf 670 seats directly upon the sills, without the use of support strips, such as 69. The front edge of the shelf, in this instance, contacts the inner top portion 75 of bottom molding 68, and projects somewhat above said molding.

A form of bottom ledge 72 is illustrated in Fig. 3. The molding 68 is not utilized with this form. The support strips 73 extend forwardly of the unit and are there provided with a ledge member 74, and angularly disposed price tag strip 75, and bottom molding 76. Strip 73 terminates behind and interlocks with the front sill 25. Suitable end pieces 77 close the open end of the ledge structure. This ledge is especially adapted for use with vertical frames 94 to be described. Plain shelves 720 may be seated upon the bottom end 89 of said frames.

The supporting means for the regular shelves comprise pins 78 (Figs. 6 and 7) having a body portion 79 receivable in the perforations 39 of the partition 38, and provided at each end with a headed shank 80 projecting outwardly of the partition. Key-slotted angle brackets 81 are receivable upon said headed shanks and provide ledges 82 upon which the shelves 83 are supported. The end walls 41 of a unit are provided, in their perforations 39, with support pins 85 (Fig. 5) having only one headed shank which projects inwardly of the unit, the outer ends of the perforations being closed by veneer strip 42, as previously described. The shelves are provided with endwise notches 84 for receiving the bracket 81 and headed shank 80, whereby movement of the shelves is precluded. As illustrated in Fig. 1, the shelves 83 may be provided with label strips 71 along their front edges. If desirable, the shelves, as shown in Fig. 18, may be angularly disposed by supporting them upon brackets the front and rear pairs of which are at different heights. The notches 84 in this case are of somewhat greater length. Such adjustments are possible due to the freely pivoting movement of the support brackets 81 upon their pins. A support rail 86 (Figs. 1, 18) for goods placed upon the shelves may be disposed longitudinally of the shelves upon vertical pins 87 fixed in and extending upwardly of the shelves.

In Figs. 3 and 12 to 17, means for continuous shelving are illustrated. The solid panel type of partition is replaced by an open frame or ladder type 94. This consists of a rectangular frame having the sides or stiles 88 and ends 89 of the same thickness as one of said partitions. The inner opposed edges of stiles 88 are grooved along their length, as

indicated at 90, and the resulting flanges 91, are provided with oppositely disposed bores 93 for the reception of pins 92.

For supporting continuous horizontal shelving a shelf rest 95 (Figs. 14, 15) is provided. This consists preferably of a metal strip having its central longitudinal section formed to provide a body portion 96, U shaped in cross section, and its lateral sections turned outwardly in a common plane to provide flanges 97, which are cut off short of the ends of the body 96. Adjacent each end of the body, the base is notched as at 98. The ends of said body are adapted to fit snugly in the grooves 90 of the stiles 88 and one of the pins 92 is receivable in the notch 98 at each end of the body 96, whereby the shelf rest is supported transversely of the frame 94. The shelf rests 102 used in the end frames of a unit are illustrated clearly in Figs. 13, 16, 17. In these the distance between the sides of the body portion 103 is substantially half that of the shelf rest previously described. A single flange 97 is provided on each, said flange being adapted to project inwardly of the unit. The bore 93 of the end frames is not completed through the outermost stile flange 91. A panel such as the veneer panel 99 is positioned within the end frames abutting the members 102. The panel may be retained in place by corner molding 100 attached to inner edges of stiles 88 and ends 89 of the frame and to the lateral face portions of the panel, (Figs. 12, 13, 16). The shelves 101 are supported upon the flanges 97 and are provided with notched corners embracing stiles 88 as far as the longitudinal centers of said stiles (Figs. 12 and 14).

In the event it is desired to dispose the shelves angularly each shelf rest is supported upon pins at different heights. Such disposition necessitates the use of somewhat longer shelf rests to compensate for the inclination, the essential structure being otherwise the same, moreover the shelves should preferably be of somewhat greater width.

To permit the abutting shelves in adjacent sections of a unit being disposed at different inclinations, it is obvious that shelf members 102 may be pivotally moved, upon the same pin to non-aligned relationship.

New units may be added to the first unit, erected as described, by replacing the end walls 41 or the end frames 94, with partitions 38 or with unpaneled frames 94, depending upon whether or not the erected unit is of the continuous shelving type. The single-headed shelf support pins are replaced with double-headed pins. After such replacements, a pair of sills 25 may be attached at either or both ends of the erected unit, by inserting the tongues 28 into the pockets 35, and 45, at all times accessible at both ends of the unit. Thereafter, the erecting process is identical with that heretofore described. In

this way the shelving installations of this invention may be increased or decreased as needed in varying circumstances and locations.

What is claimed is:

1. Knockdown shelving units each comprising base members, vertical members supportable by the base members, top members and means for removable attachment thereof to the vertical members, shelves and means for removable positioning thereof between the vertical members, and upwardly-opening receiving members and downwardly-projecting tongue members associated with the base and providing for the addition of other units to the erected shelving unit. 70

2. In a shelving unit, the combination with removable base, top and perforated vertical members, of pins insertable in the perforations of said vertical members and having ends adapted to project outwardly of the perforate members, bracket members each adapted to be pivotally and removably supported upon one of said projecting ends, and shelves adapted to be removably supported upon said brackets. 75

3. In a knockdown shelving unit, the combination of a pair of sill members tenoned at one end and cross gained intermediate their ends, an upwardly-opening receiving member attached to the tenoned ends of said sills, downwardly-projecting tongue members attached upon the opposite ends of the sills, a perforate partition having a mitred bottom edge adapted to cooperate with the cross gaining of the sills for supporting the partition, a pair of end walls perforated and mitred similarly to said partition, one of said walls being receivable upon said tenoned ends between said receiving members and the body portions of the sills, a pair of U-shaped shoe members receivable in the mitred portions of the other end wall and adapted upon positioning to provide upwardly-opening pockets, said tongue members of the sills being receivable one each in one of said pockets for supporting said end wall, top members, cooperating means on said members and on the partition and end walls for removably joining all of said members, bottom shelves supportable upon the sills and provided with means precluding movement of the shelves transversely of the unit, headed pins insertable in the perforations of partition and walls and projecting inwardly of the unit, brackets removably supported upon said pins, and shelves supportable upon the brackets and provided with means precluding movement thereof transversely of the unit, the outer portions of said receiving and pocket members being adapted for attachment with other sills whereby similar units may be added to the erected shelving unit. 80

4. In a knockdown shelving unit, the combination of sill members, a perforate parti- 85

- tion and perforate end walls adapted to be supported by said sills, top members and means for attachment thereof to the partition and end walls, bottom shelves supportable upon the sills, pins insertable in the perforations of the partition and end walls and having heads adapted to project inwardly of the unit, brackets removably supportable upon said pins, shelves supportable upon the brackets, means substantially precluding movement of the shelves transversely of the unit, and means on the sills for attaching similar units to the erected shelving unit. 5. In a shelving unit, the combination of sill members adapted for spaced parallel positioning, receiving members at one end of the sills, tongue members attached at the other end of the sills, a pair of wall members, one wall of the unit being supportable by said receiving members, and U-shaped shoe members adapted to be positioned upon the base of the other wall and to receive the tongues of said tongue members for supporting said other wall, said receiving and shoe members providing means on the exterior of the walls for attachment thereto of the sills of additional units. 6. In a shelving unit, the combination of base members, vertical panels supportable upon the base members and provided with rows of aligned perforations, top members, cooperating means on the panel and top members for removable connection thereof, double-headed pins insertable in the perforations of intermediate panels, single-headed pins insertable in the perforations of the end panels, the heads of said pins projecting inwardly of the unit, key-slotted brackets pivotally receivable upon said heads, and shelves supportable upon the brackets and slotted to receive the heads and brackets for precluding movement of the positioned shelves transversely of the unit. 7. In a shelving unit, the combination of base members, vertical panels supportable upon the base members and provided with rows of aligned perforations, top members, cooperating means on the panel and top members for removable connection thereof, double-headed pins insertable in the perforations of intermediate panels, single-headed pins insertable in the perforations of the end panels, the heads of said pins projecting inwardly of the unit, key-slotted brackets pivotally receivable upon said heads, shelves supportable upon the brackets and slotted to receive the heads and brackets for precluding movement of the positioned shelves transversely of the unit, means closing the outer ends of the perforations in the end panels, and means associated with the base members for attaching similar units to the erected shelving unit. 8. In a shelving unit, the combination of base members, vertical panels supportable upon the base members and provided with rows of aligned perforations, top members, cooperating means on the panel and top members for removable connection thereof, double-headed pins insertable in the perforations of intermediate panels, single-headed pins insertable in the perforations of the end panels, the heads of said pins projecting inwardly of the unit, key-slotted brackets pivotally receivable upon said heads, and shelves supportable upon the brackets and slotted to receive the heads and brackets for precluding movement of the positioned shelves transversely of the unit, said brackets being adapted to retain shelves in horizontal and inclined positions. 9. In a knockdown shelving unit the combination of base members, a partition and end walls supportable upon the base members, top members, means on the top, partition and end members for separably connecting said members, shelves and removable shelf-mounting means attachable to the partition and end walls, complementary molding structure on the top partition and wall members, and covering pieces secured to members of the unit and adapted to cover abutment lines of the separable members upon assembling of the unit. 10. The combination in a continuous shelving unit, of base members, rectangular frames provided with a groove and perforate flanges along their opposed longitudinal edges, means for supporting the frames transversely of the base members, top members, cooperating means on the frames and top members for removably connecting said members and frames, pins insertable in the perforations of said edge flanges and adapted to extend across said groove, shelf rests adapted to extend transversely of the frames, said shelf rests comprising each a body portion having ends insertable in said grooves and pivotally supportable upon a pair of said pins and flanges extending at substantially right angles to said body portions, and shelving adapted to extend through said frames and to be supported upon the flanges of the shelf rests. 11. The combination in a continuous shelving unit, of base members, rectangular frames provided with a groove and perforate flanges along their opposed longitudinal edges, means for supporting the frames transversely of the base members, top members, cooperating means on the frames and top members for removably connecting said members and frames, pins insertable in the perforations of said edge flanges and adapted to extend across said groove, shelf rests adapted to extend transversely of the intermediate frames of the unit, said shelf rests comprising each a body portion having ends insertable in said grooves and supportable upon a pair of said pins and divergent flanges ex-

tending at substantially right angles to said body portion, similar shelf rests for positioning in the end frames of the unit and providing each a single flange extending inwardly of the unit, continuous shelving adapted to extend through said frames and to be supported upon the flanges of the shelf rests, and panels adapted to be positioned in the end frames against the shelf rests therein.

12. The combination in a continuous shelving unit, of base members, rectangular frames provided with a groove and perforate flanges along their opposed longitudinal edges, means for supporting the frames transversely of the base members, top members, cooperating means on the frames and top members for removably connecting said members and frames, pins insertable in the perforations of said edge flanges and adapted to extend across said groove, shelf rests adapted to extend transversely of the frames, said shelf rests comprising each a body portion having ends insertable in said grooves and pivotally supportable upon a pair of said pins and a flange extending at substantially right angles to said body portion, units of shelving adapted to extend through said frames and to be supported one each upon a pair of said shelf rests, each pin of the intermediate frames being adapted to support two of said shelf rests whereby adjacent shelf rests and shelves may be disposed in unaligned relationship, and panels adapted to be positioned in the outer portions of the end frames and in abutment with the shelf rests supported therein.

13. In a shelving structure, the combination with shelves and vertically-supported rectangular frames having a pair of perforate flanges along the opposed longitudinal edges thereof, of a shelf rest comprising a body portion having each end notched at the bottom thereof and insertable between said flanges, a ledge portion extending outwardly of said body portion, and pins insertable in the perforations of said flanges and adapted to extend transversely thereof, the notches of the shelf rest being receivable by a pair of said pins for supporting the shelf rest transversely of a frame, and the shelves being supportable upon the ledges of shelf rests so positioned.

In testimony whereof, I have hereunto subscribed my name this 23rd day of January, 1931.

EDWARD C. CORDES.
